INJECTION BLOW MOLDING MACHINE

Katashi Aoki, 6037 Oaza Minamijo, Sakaki, Japan

Filed Dec. 14, 1972, Ser. No. 315,136

Term of patent 14 years

Int. Cl. D15—09

U.S. Cl. D55—1 F

FIG. 1 is a front elevation view of an injection blow molding machine in accordance with the design of the invention;

FIG. 2 is a left end elevation view of the machine of FIG. 1 viewed from the left in FIG. 1;

FIG. 3 is a right end elevation view of the machine of FIG. 1 viewed from the right in FIG. 1;

FIG. 4 is a top view of the injection blow molding machine of FIG. 1; and

FIG. 5 is a rear elevation view of the injection blow molding machine of FIG. 1.

I claim:

The ornamental design for an injection blow molding machine, as shown.
